(57) CLAIM

The ornamental design for a box, as shown and described.

DESCRIPTION

FIG. 1 is a perspective view of a box showing my new design;

FIG. 2 is a front elevational view;

FIG. 3 is a rear elevational view of FIG. 2;

FIG. 4 is a top plan view of FIG. 2;

FIG. 5 is a right side elevational view of FIG. 2; and,

FIG. 6 is a left side elevational view of FIG. 2.

The stippling in the drawings is to show contrasting color.
